UNITED STATES PATENT OFFICE.

VITAL CESAR, OF BRUSSELS, BELGIUM.

CONTROLLING DEVICE FOR SIGNALS HAVING SEVERAL POSITIONS.

1,418,127.

Specification of Letters Patent. Patented May 30, 1922.

Application filed June 28, 1920. Serial No. 392,489.

To all whom it may concern:

Be it known that I, VITAL CESAR, a citizen of the Kingdom of Belgium, and resident of Brussels, Belgium, have invented certain new and useful Improvements in Controlling Devices for Signals Having Several Positions; and I do hereby declare the following to be a full, clear, and exact description of the invention, such as will enable others skilled in the art to which it appertains to make and use the same, reference being had to the accompanying drawings, and to letters or figures of reference marked therein, which form a part of this specification.

This invention relates to an improved signal for use in connection with railroads and is of the semaphore type. One object of the invention is to provide a signal of the character described having improved actuating means including means for imparting movement to the semaphore or signal board and improved means for releasably holding the board in a set position.

Another object of the invention is to so construct the operating means that the means for imparting movement to the board may also serve as means for releasably locking the board in a set position.

Another object of the invention is to provide operating means which will be very efficient in operation and easy to operate.

The appended drawings show by way of example an embodiment of the invention. Figs. 1 to 4 shown diagrammatically a signal 35 with its actuating means, in four different positions. Fig. 5 is a perspective view of the mechanism A of the Figs. 1-4.

The mechanism comprises a plate 1 furnished with a notch 3 and a stop piece 5; a 40 plate 2 with a notch 4, and a stop-piece 6; a hammer 7 engaging in the notches 3 and 4 and a rod 9; connecting this hammer with the signal or wing P, having three positions P, P', P''. A cross-piece 8 which can run 45 against the stop pieces 5 and 6 is riveted on the hammer 7.

The plates are displaced by means of the levers 10 and 11 with which they are respectively connected by rods 12 and 13, usual 50 levers 14 and 15 and funicular transmissions 16-16' and 17-17'.

The limits in motion of the plates are fixed by stop pieces 18 and 19 for the first and 20 and 21 for the second. A counter-weight 22 —which rests normally on a regulatable 55 support 25 is threaded on an arm 23 pivoting on the axis 24.

As represented in the drawings and in accordance with what follows, the combination of the notches 3 and 4 with the cross piece 8 60 and stop-pieces 5 and 6 makes the hammer interdependent with the notched plates in such a manner that it must move, and with it the signal, into the position corresponding with that of the working lever or levers. 65

The notched plates, as also the hammer, are guided in their movements by ordinary means not represented in the drawings.

In Fig. 1 the position P of the signal is determined by the stop piece 18, the plate 1, 70 the hammer 7 hooked in this plate and the rod 9. The device, 18-1-7-D is considered to be rigid as regards the position it gives to the signal, because it is constructed so that it can neither increase nor decrease 75 in length to any appreciable degree. The position P which it assures is thus invariable.

Upon the lever 10 being actuated, the mechanism takes the position of Fig. 3 this 80 position P' of the signal is also invariable in this sense that it is assured in the same way as the position P; in fact, the hammer 7 is hooked in the plate 2 and the latter rests on the stop piece 20. 85

Upon the lever 11 being actuated after the lever 10, the mechanism takes the position of Fig. 4 which is assured by the fact that the plate 1 in which the hammer is hooked to support the signal, is pressed against the 90 stop-piece 19.

In examining the drawings it will be seen that the plates 1 and 2 are respectively in contact sometimes with the stop pieces 18 and 20, sometimes with the stop pieces 19 95 and 21.

This condition is assured, as regards pressure against the stop-pieces, 18 and 20 by the cams 27 and 29 which realize a greater traction on the wires 16 and 17 than on the 100 wires 16' and 17', and they also compensate elongation of these wires owing to the

greater strain to which they are subjected.

As for pressure of the plates against the other stop-pieces 19 and 21 it is realized in the same manner by aid of the cams 28 and 26.

To bring the signal to one of the positions P, P', P'', the operation is as follows:

For position P, the two levers 10 and 11 which are hand operated are brought into position N, that is to say the normal position or that of stoppage.

For position P' the lever 11 is left in the normal position and lever 10 reversed. Thus the plate 1 is drawn away from position B to position C, then to position D. The hammer 7 which is normally hooked in the notch 3 cannot disengage itself owing to the presence of plate 2 must follow the movement and lift the signal through the agency of the rod 9. However when it reaches position C, or the height of the notch 4, it enters this notch because the lever 14 swings downwardly in the arc of a circle and therefore has a tendency to move the plate 1 over toward the plate 2 and further the cross-piece 8 strikes the stop 6 and this stops downward movement of the hammer thus causing the cam faces of the hammer and notch 3 to move the hammer out of the notch 3 into the notch 4 as the plate 1 continues downward movement from the position C toward position D. As the plate continues downward movement, its inner side edge face engages the end of the hammer 7 and thus the hammer will be prevented from moving out of the notch 4.

To realize the position P'', starting from position Fig. 3 it suffices to reverse the lever 11. It is evident that the latter will move the signal through the agency of plate 2, of hammer 7, and of rod 9, until the hammer reaches and enters, for reasons previously given in the case of position P', the notch 3, corresponding at this instant to positions P''.

We can also realize the position P'' in starting from the situation Fig. 2, which situation is obtained by reversing the lever 11 and leaving lever 10 locked.

It will be seen that it suffices to then reverse the lever 10, in its turn, to obtain the position represented in Fig. 4.

In passing from the position of Fig. 1 to the position of Fig. 3, the plate 1 is in interlocked engagement with the hammer 7 from position D to position C, but in passing from position C to position D, the plate 1 moves out of engagement with the hammer 7 and therefore the weight of the signal board and hammer no longer offers resistance to movement of the plate 1. The resistance offered by this weight would thus be removed and this sudden removal of resistance would cause the lever to suddenly move very easily and there would be danger of an operator being injured or of portions of the device

being broken by the lever suddenly moving rapidly when the weight resistance is removed.

To avoid this inconvenience the counter-weight 22 is utilized as follows: At the moment when the hammer 7 enters the notch 4 the plate 1 comes into contact with the arm 23 and raises the counter-weight. The latter then takes the place of the signal board to assure continuation of the stress to be exerted on the lever.

It is also the same with regard to lever 11, at the instant, when in passing from position of Fig. 3 to position of Fig. 4 the hammer enters notch 3.

The peculiar inclination given to arm 23 must also be noted. The object of this inclination is to prevent the plates ever raising the counter-weight when they are loaded with the wing. This condition is clearly indicated in the drawings which also show that the plate engaged with the counter-weight is drawn to stoppage by the said counter-weight.

What I claim is:

1. A device to control a railway signal which can be moved to three different positions comprising an entrained part connected with the signal to be moved, two entraining parts moved by distinct levers, fixed stop pieces limiting the displacement of said two entraining parts and suitable connections effective alternately between said entraining parts and the entrained part, in such a manner that each of the entraining parts can, during part of its course, entrain the part connected with the signal, then continue its course after movement of said part has been stopped by connection with the other entraining part.

2. A device to control a railway signal which can be moved to three different positions, comprising a reciprocating hammer connected with the signal, a moving plate on each side of said hammer, fixed stops limiting the displacement of said two plates, distinct levers and connecting means for moving said two plates, a notch with oblique sides in one of the plates, in which one of the faces of the hammer is engaged when the signal is in the closed position, and a similar notch provided in the other plate and so arranged as to receive the hammer after a certain displacement of the latter under the action of the first plate.

3. A device to control a railway signal which can be moved to three different positions, comprising a reciprocating hammer connected with the signal, a moving plate on each side of said hammer, fixed stops limiting the displacement of said two plates, distinct levers and connecting means for moving said two plates, a notch with oblique sides in one of the plates, in which one of the faces of the hammer is engaged when

- the signal is in the closed position, and a similar notch provided in the other plate and so arranged as to receive the hammer after a certain displacement of the latter under the action of the first plate, a cross-piece on the hammer and fixed pins in the plates acting on said cross-piece to make the hammer reciprocate and engage in the notches of the plates.
- 10 4. A device to control a railway signal which can be moved to three different positions, comprising a reciprocating hammer connected with the signal, a moving plate on each side of said hammer, fixed stops limiting the sliding movement of said two plates, separate levers and connecting means for moving said plates, one plate having a
- 5 notch with oblique sides, in which one of the faces of the hammer is engaged when the signal is in the danger position, and the other plate having a notch arranged to receive the hammer after a certain displacement of the latter under the action of the first plate, and a counterweight adapted to be worked by the plates and to move them 25 back towards the positions corresponding to the danger position of the signal.
- 15 In testimony whereof I affix my signature in presence of two witnesses.

VITAL CESAR.
